(57) **CLAIM**

The ornamental design for a power bank, as shown and described.

DESCRIPTION

FIG. 1 is a top front perspective view of a power bank;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom elevation view thereof; and,

FIG. 8 is an exploded perspective view thereof.

The broken lines in the drawings are for the purpose of illustrating portions of the power bank that form no part of the claimed design.
